UNITED STATES PATENT OFFICE.

EDWARD ERICKSON, OF WEST LYNN, MASSACHUSETTS, ASSIGNOR, BY DIRECT AND MESNE ASSIGNMENTS, TO VICTOR SHOE MACHINERY COMPANY, OF BOSTON, MASSACHUSETTS, A CORPORATION OF MASSACHUSETTS.

LOCK-STITCH SEWING-MACHINE.

1,137,198.

Specification of Letters Patent. Patented Apr. 27, 1915.

Application filed December 28, 1912. Serial No. 739,056.

To all whom it may concern:

Be it known that I, EDWARD ERICKSON, a citizen of the United States, and resident of West Lynn, in the county of Essex and State of Massachusetts, have invented certain new and useful Improvements in Lock-Stitch Sewing-Machines, of which the following is a specification.

This invention relates to machines for sewing heavy material such as leather, and refers particularly to that type of such machines known as welt sewing machines.

One of the objects of the invention is to provide a machine of this character which will enable repair work to be done on shoes where it is desired to continue the seam well along the shank toward the heel of the shoe that is being repaired, or start sewing close to the heel.

Further objects are to provide an improved needle-actuating mechanism and preferably through which the awl is also oscillated; to provide for a dwell in the motion of the needle so as to release the thread to avoid liability of the shuttle stripping the thread; to provide means carried by the needle support for making the loop; to provide an improved parallel bar motion operating mechanism for driving the shuttle; and to provide further improvements which I shall now proceed to describe and claim.

Of the accompanying drawings: Figure 1 is a front elevation of the machine complete; Fig. 2 is an elevation from the left of Fig. 1; Fig. 3 is an elevation from the right of Fig. 1, but with portions at the extreme right of said figure broken away; Fig. 4 is a view similar to Fig. 3, but illustrating more in detail the mechanism behind parts shown in Fig. 3; Fig. 5 is a part elevation in part section on a vertical line substantially midway of the machine; Figs. 4 and 5 are in fact elevations of parts which would appear if the mechanism shown in Fig. 1 were divided substantially centrally and opened out; Fig. 6 is a plan view of the machine; Fig. 7 is a detail elevation of one of the cams shown in Fig. 6, but in a different position of rotation; Fig. 8 is a detail elevation of the shuttle and its support; Fig. 9 represents a section on line 9-9 of Fig. 8; Fig. 10 is a view similar to Fig. 9, but showing the bobbin support turned outwardly; Fig. 11 represents a section on line 11-11

of Fig. 8 on an enlarged scale; Fig. 12 represents a section on line 12-12 of Fig. 11, and also on line 12-12 of Fig. 8, but on a larger scale than Fig. 8; Fig. 13 is a detail elevation of the presser foot and its bar and operating mechanism; Fig. 14 is a view similar to Fig. 13, but looking in the opposite direction; Fig. 15 is a detail view, partly in section, of portions of the machine herein-after described; Fig. 16 is a detail view of the thread lock; Fig. 17 represents a section on line 17-17 of Fig. 16; Fig. 18 represents a section on line 18-18 of Fig. 16; Fig. 19 represents a section on line 19-19 of Fig. 1; Fig. 20 represents a section on line 20-20 of Fig. 19; Fig. 21 is a detail, partly in section, of some of the operating parts hereinafter described; Fig. 22 represents a section on line 22-22 of Fig. 21; Fig. 23 is a detail view illustrating the construction and operation of the take-up.

Similar reference characters indicate the same or similar parts in all of the views.

The base 30 of the machine is provided with two uprights or standards 31, 32, said base being made in two parts, as indicated in Fig. 1, the standards having suitable abutting portions, to enable tie screws or bolts 33 to be passed through said abutting portions and the two parts of the base to hold the frame of the machine rigidly together.

The main shaft 34 is supported in a bearing 35 in the standard 31 and in a bearing 36 carried by a bracket 37, which is bolted to the side of the standard 32. Said main shaft has a driving pulley 38 at one end and at its other end is provided with a spiral gear 39 meshing with a pinion 40 secured to a shaft 41 mounted in a bracket 42 supported by the top of the standard 31. The gear 39 and pinion 40 are as 3 to 1.

The opposite ends of the shaft 41 are provided with cranks 43, 44 substantially at an angle of 90° to each other. A shaft 45 also mounted in the bracket 42 is provided with cranks 46, 47 at substantially an angle of 90° to each other. A pitman 48 connects the cranks 43 and 46, and a pitman 49 connects the cranks 44 and 47. The pitman 49 has an extension or finger 50, the extreme tip of which forms or carries a lateral pin 51 which enters a recess 52 in the shuttle 53 (Figs. 2 and 4). The connections just de-

scribed, including the parallel links 48, 49, impart a smooth, uniform motion to the shuttle to rotate the latter three times to each rotation of the main shaft.

5 Referring especially to Figs. 2, 8, 9 and 10, it will be seen that the shuttle 53 is provided with a rib 54 running in a groove formed in the two-part bearing bracket 55, 56, these two parts of the bearing bracket 10 being formed to present a circular support for the shuttle, one side of the support being open of course to permit the loop of needle thread to be engaged by the hook of the shuttle, carried around the shuttle and 15 removed again therefrom by the take-up. As shown in Figs. 6 and 8, a screw 57 connects the two parts 55, 56 of the shuttle supporting bracket together, attaching bolts 58 securing the two parts of the bearing 20 bracket to the inner face of the standard 31. As best shown in Fig. 6, all of the parts so far described are arranged and mounted to present the shuttle in a plane tangential to the path of operation of the needle and awl.

25 The bobbin 59 (Figs. 8, 9 and 10) is rotatably supported upon a pin 60 projecting from an arm 61 pivoted at 62 to the shuttle, said arm 61 having a heel or lateral projection 63 by means of which, as 30 presently described, the bobbin and its support may be locked in the position shown in Fig. 9. A spring 64 secured at one end to the shuttle supporting bracket bears at its other end against the bobbin to hold 35 the bobbin on the pin 60 and also to provide tension to prevent a too free unwinding motion of the bobbin. The heel 63 is provided with a pin 65 having a flat side and a round side, as shown in Figs. 11 and 40 12, said pin 65 being adapted to enter the recess 67 of the latch bolt 66, which is mounted in the shuttle body, a projection 68 at one side of the recess 67 forming a keeper to engage the pin 65 when in the position shown in Fig. 12, and consequently 45 lock the bobbin arm 61 in the position shown in Fig. 9. The engagement of the keeper 68 with the pin 65 is preserved by a spring 69 confined between the inner end of the latch 50 bolt 66 and the plug 70 threaded into the inner end of the aperture for bolt 66. Whenever it is desired to remove the bobbin for re-winding or to substitute another bobbin for it, pressure against the end of the 55 latch bolt 66 by any suitable implement disengages the keeper 68 from the pin 65 so that the operator, by pushing with one finger against the side of the bobbin which sustains the pressure of spring 64, may 60 swing the bobbin and its support to the position shown in Fig. 10 so that the bobbin can easily be removed from the pin 60. By then simply swinging the support 61 from the position shown in Fig. 10 back to the 65 position shown in Fig. 9, the round side of the pin 65, when it contacts with the keeper 68, acts as a cam to displace the keeper 68 to permit the pin 65 to pass it, after which the spring 69 causes the latch bolt 66 to return to the position shown in Fig. 12.

The work support 71, provided with the usual slot of course to permit of the feeding motion of the awl, is carried by the outer end of an arm 72 secured to the standard 31, as by means of screws 73 (Fig. 1). 70 As shown by comparing Figs. 1, 2 and 6, reference being had especially to the latter, it will be seen that the arm of the work support has its outer face extending abruptly rearwardly from the portion which supports 80 the work, so that there will be no obstacle to the passage of a shoe being repaired far enough to permit sewing to be done along the shank of the shoe. In other words, the outer face of the work support is so formed 85 that the heel of a completed shoe which is being repaired will not interfere with the presentation of the work to the work support 71 to permit sewing to be carried along the shank of the shoe. The point at which 90 the arm 72 is secured to the frame is so far away from the path of movement that would have to be imparted to the heel of a shoe, and the arm 72 extends outwardly from said point of support at such an 95 abrupt angle that neither the work support nor its arm presents any obstacle to sewing as described along the shank of the shoe. In order that the frame of the machine will 100 present no obstacle to the movement of a shoe far enough to permit the seam to be started from a point close to the heel at one side and to be continued close to the heel at the other side of the shank of a shoe, said frame is recessed, or cut away, or reduced, 105 as shown at 72^a by comparing Figs. 1 and 6. In brief, the particular form of the work rest illustrated and described, in connection with the cut-away or reduced portion 72^a of the frame, enables a seam to be started 110 and continued along the shank quite close to the heel on repair work.

The arm 74 having the presser foot 75 (Fig. 1) is secured, by means of suitable screws or bolts, in a recess 76 (Figs. 5 and 115 13) of an arm 77 of a lever, the other arm 78 of which is formed or provided with a segment rack 79 meshing with a pinion 80. The lever 77, 78 is pivotally supported on a sleeve 81 indicated by dotted lines in Fig. 120 5, which sleeve is supported as hereinafter described. The pinion 80 has a sleeve hub 82 mounted loosely upon a pin or stud-shaft 83 eccentrically carried by a disk 84 (Figs. 14 and 15), said disk being carried by a stud shaft 85 mounted in an arm 86 of the standard 32. A split ring 87 is clamped upon the disk 84, as by means of a binding screw or bolt 88, said ring 87 having an arm 89 provided with a roll 90 engaging a cam groove 130

91 in one side of a cam hub 92 carried by the shaft 34, whereby, prior to the feeding of the work, the pin 83 on which the pinion 80 is mounted is oscillated relatively to the 5 axis of the stud shaft 85 and lifts the presser foot from contact with the work and permits the latter to be fed. After the work has been fed the pin 83 is returned to its normal position thus moving the presser 10 foot into gripping contact with the work. The split ring 87 enables an adjustment to be effected between the arm 89 and the disk 84.

To cause the presser foot to bear with 15 yielding pressure upon the work, I employ a spring 93 (Fig. 15), one end of said spring being connected to the pinion 80 and the other end connected to a collar 94, the latter having a series of radial notches 95 in its 20 outer end, with either one of which a pin 96 projecting from pin 83 is adapted to be engaged. The pin and notch construction just described is for the purpose of enabling the tension of spring 93 to be adjusted so as to 25 force said spring to act through the pinion 80 and the segment-toothed arm 78 to lower the presser foot 75.

To effect the locking of the presser foot to hold the work tightly during the formation 30 of each stitch, and to release it during the feed of the work, I provide the following mechanism. Mounted upon the sleeve hub 82 of the cam 80 are the two recessed hubs 97, 98, a spring 99 being located in the recess and adapted, as presently explained, to act as a brake upon the outer periphery of the sleeve hub 82. One end of said spring is connected to the hub 98 and the other to the hub 97. The latter has an arm 100 provided with a pin 101 which enters a slot in an adjustably fixed arm 102 pivotally connected at 103 to the standard 32 (Fig. 5). The lower end of the arm 102 is formed with an arc slot 104 (Fig. 13) through which a 45 binding screw 105 passes into the standard. This provides for so adjustably securing the arm 102 as to vary the position of the hub 97 rotatably to slightly loosen or tighten the brake spring 99 as may be necessary to insure the accurate operation of said spring 50 as a brake.

The hub 98 has an arm 106 (Fig. 13) which is connected by a link 107 to one arm 108 of an elbow lever pivoted at 109, the 55 other arm 110 having a roll which engages a cam groove 111 in the side of the cam disk 92. The pivot 109 is a pin which extends through the standard 32 and projects at each end from said standard, being mounted 60 to oscillate in a hole in said standard. At one end, this pin 109, which is practically a rockshaft, has a pinion (Fig. 5) meshing with a rack 113 carried by a vertically movable rod 114, which may be connected to a 65 treadle not shown to raise the presser foot

when work is to be introduced. The other end of the rockshaft 109 is provided with a cam-shaped projection 116 (Figs. 3 and 14) which enters an opening in one end of a pivoted arm 117, said arm being pivotally connected at 118 to the arm 110 of the elbow lever. The arm 117 has a roll 119 which bears against the periphery of the cam disk 92, the latter having a recess or depression 120. As will be readily understood, when 70 the parts occupy the relative positions shown in Figs. 13 and 14, the arm 117 forms practically a rigid portion of the arm 110 of the elbow lever, the rolls carried by these two arms engaging opposite sides of the 80 rib of the cam disk 92 which separates the cam groove 111 from the periphery of the cam, and therefore as the cam disk rotates the elbow lever is oscillated, the structure and operation of the parts being such that 85 when the operative portion of the cam groove 111 reaches the roll or arm 110 the elbow lever is oscillated to tighten the brake spring 99 (Fig. 15), this occurring during the formation of each stitch. As will be explained hereinafter, the operation of the foot treadle rod 114 acts to oscillate the rockshaft 109 to rotate the cam projection 116 sufficiently to allow relative movement 90 of arms 110, 117 so as to permit the presser foot to be raised regardless of the rotative position of the cam disk 92.

As best shown in Fig. 13, the inner wall of the cam groove 111 is provided with a recess 121 which, when it arrives opposite 100 the roll of the arm 110, will permit said roll to move toward the axis of rotation of the cam disk 92 so as to relieve outward pressure on said roll and thus release the braking effect of the brake spring 99 and permit 105 the presser foot to be lifted.

The take-up arm 125 (Fig. 5) is pivotally connected at 126 to one end of a shaft 127, the pivot connection of the take-up lever or arm being eccentric to the axis of the shaft 110 127, as shown in Figs. 5 and 13. The bearing for the shaft 127 is indicated at 130 in Fig. 5. The take-up arm is provided with two rolls 128 (Figs. 5 and 23), a roll 129 being stationarily mounted. The other end 115 of shaft 127 is provided with an arm 131 (Fig. 13) which is sweated or otherwise secured to said shaft, said arm 131 being connected by a link 132 with the arm 78 of the presser foot lever. As shown in Fig. 23, a 120 roll 133 is stationarily mounted, the needle thread α passing from the thread lock 134 hereinafter described, and over the roll 133, under rolls 128 and to the needle. The stationary roll 129 is in such position that 125 when the take-up lever moves downwardly toward and to the position indicated by dotted lines in Fig. 23, the thread will be taken up in two loops instead of one as customary heretofore, so that the take-up needs 130

to have imparted to it but one half the usual motion of throw. The short arm of the take-up lever is provided with a roll 135 which is acted upon by a cam 136 (Fig. 4), 5 the take-up lever being actuated so as to keep the roll 135 in contact with the cam by means of a suitable spring such as indicated at 137 in Fig. 23. The structure just described varies the throw of the take-up 10 according to the thickness of the work. Referring to Fig. 13, if the presser foot 75 is held in a higher position than shown, due to the presence of thicker work between it and the work rest, the connection by means 15 of the link 132 oscillates the shaft 127 so as to shift the position of the pivot 126, thus changing the position of the fulcrum of the take-up arm to increase the throw of the take-up lever.

20 The structure of the thread lock is best illustrated in Figs. 16, 17 and 18, a stud 138 projecting from the standard 32 having a reduced portion to form a pin 139 on which is mounted, to rotate freely when permitted 25 to do so, a sleeve 140 having an enlarged portion 141 provided with an annular groove 142. A spring 143 is coiled about the outer surface of sleeve 140 and has one end anchored to the fixed stud 138, the other end 30 being turned outwardly to form a hook 144 (Figs. 5 and 17). This hook is engaged by a pin 145 projecting from an arm 146 of a rock-shaft 147, said rockshaft having another arm 148 provided with a roll 149 actuated by a cam 150 on the main shaft 34, said cam being cut away, as best shown in Fig. 5, so that when the cutaway portion reaches the roll 149, the rockshaft 147 is released so 35 that the pin 145 will move away from the position shown in said figure. It is to be understood that, when the parts are in the position shown in Fig. 5, the coil spring 143 is gripped tightly upon the sleeve 140 so as to act as a brake. Consequently, when the 40 thread is laid with one or more turns in the groove 142 (Fig. 18) said thread will be practically locked because of the action of the braking spring 143 until the recessed portion of the cam 150 releases it in the manner just described.

45 The needle 151 has its carrier 152 (Fig. 4) pivotally mounted on the fixed pin 153. The carrier 152 has a rearwardly projecting arm 154 connected by a link 155 with an arm 156 which is fixedly but adjustably secured to 50 one end of a rockshaft 157 (Figs. 2, 4, 21 and 22) mounted in two disks 158, 159 carried by a rockshaft 160 which is mounted to oscillate in a bearing 161 of the frame of 55 the machine. Said bearing is cut away in the form of an arc slot 162 so that the rockshaft 157 can be shifted by the oscillation of the disks as presently described. The disk 158 and the rockshaft 160 are oscillated by means of a pitman 163 (Fig. 2), the

upper end of said pitman being formed as an eccentric strap embracing a circular disk which really constitutes a crank pin 164 secured to the face of the gear 39, as by screws 165. The casting which forms this crank 70 pin or eccentrically mounted disk is also formed with another disk-shaped portion 166, as indicated by dotted lines in Fig. 2, this constituting another crank or eccentrically mounted disk, the two cranks or disks 75 being carried at substantially diametrical points of the axis of rotation of the gear 39. A pitman 167 connects the crank 166 with an arm 168 of the rockshaft 157.

The mechanism just described imparts a 80 peculiar motion to the needle, said needle having a dwell and slight recession of movement to release the thread so that the shuttle will not strip the latter. This motion is obtained through the operation of the two 85 parallel pitmen 163 and 167. The pitman 163 imparts a uniform motion of oscillation to the disks 158, 159, and since the said disks form bearings for the rockshaft 157, the latter of course swings within the arc slot 90 162. At the same time the pitman 167 acts through the arm 168 to rock the shaft 167 on its own axis. The resulting motion is one difficult to describe, but it is believed that it will be understood that the arm 166 at the 95 other end of the rockshaft 167 has such motion imparted to it that, through the link 155, a curved needle is reciprocated so as not only to penetrate the work and perform the usual functions of a curved sewing 100 needle, but also to have a dwell in the upper portion of this motion so as to slacken the needle thread as hereinbefore described.

I will now describe the connections for 105 operating the awl. An arm 169 (Figs. 4, 5 and 21), rigidly connected to the disk 159, has pivotally connected to its outer end a link 170, the upper end of which is pivoted to a yoke 171, which latter is in turn pivotally connected at 172 to a rearwardly extending arm of the awl carrier 173, the latter having a suitable awl 174. The pivotal connection between the link 170 and yoke 171 is transverse relatively to the pivot 172, the reason for this being to prevent strain on the operating connections when the awl carrier is reciprocated in the direction of its 110 axis of movement, when feeding.

The awl carrier 173 is mounted to oscillate on a pin 175 (Fig. 5) carried by a bracket 176 (Figs. 1, 3 and 6). The awl carrier is slid lengthwise of said pin, for feeding, by the following mechanism. A yoke 177 at the upper end of an arm 178 engages an annular groove in the hub of the awl carrier. Said arm 178 is carried by a slide 179 (Fig. 19) mounted to reciprocate in a bearing 180 formed in the frame of the machine. The slide 179 is pivotally connected at 181 to one end of a straight lever 180

182, which has an adjustable fulcrum presently described. The other end of the lever 182 has a roll 183 which enters a cam groove 184 (Figs. 1, 3 and 6) formed in a 5 disk carried by the shaft 34. By adjusting the fulcrum of the lever 182 the length of feed may be varied. I will now describe the means for adjusting said fulcrum. A suitably supported bracket 185 is formed 10 with, a cylindrical bearing 186 (Fig. 19) in which a tubular block 187 is mounted to slide longitudinally of said bearing. The block 187 is formed or provided with a rack 188 engaged by a pinion 189 rotatably 15 mounted in a suitable bearing adjacent the bearing 186, said pinion having at its lower end (Fig. 20) a stud or pin 190 on which is secured the split hub 191 of a handle 192. The said split hub is clamped on the stud 20 end 190 by a screw 193. To secure additionally the handle in place a screw 194 may be employed, said screw fitting a threaded hole in the end of the stud 190. The tubular block 187 is provided with 25 bearings for the trunnions 195 of a sleeve 196 (Figs. 19 and 20) which forms the slidably adjustable fulcrum for the lever 182. By operating the handle 192, the block 187 is shifted longitudinally, carrying with it 30 of course the fulcrum sleeve 196. The space within the block 187 is sufficiently larger than the external diameter of the fulcrum sleeve 196, to permit the latter to oscillate. Preferably the fulcrum sleeve 196 is tapered 35 toward each end, as shown in Fig. 19, to permit of such oscillations without employing a large block 187. The cam hereinbefore described which actuates the lever 182 imparts sufficient movement to the slide 179, 40 and, through the parts described, to the awl, to produce a longer or shorter stitch according to the position of the fulcrum sleeve.

As is well known, it is desirable always 45 to be able to manually adjust or vary the length of stitch within said limits, which limits are themselves adjustable. The handle 192 enables the length to be quickly and manually varied. To limit adjustably the 50 amount of variation of length of stitch, I provide the upper stud end 197 of the pinion 189 with stop fingers 199, said stop fingers being above a fixed dial or gage plate 198 (Figs. 6 and 20). The stop fingers 199 55 are provided with split hub portions which can be clamped upon the stud 197 in any desired position of adjustment, and when they have been fixedly secured as desired, they co-operate with opposite sides of a 60 fixed stop pin 200 to limit the amount of rotative movement that may be imparted to the pinion 189 by the handle 192.

The looper 201 comprises a tubular member at the outer end of an arm 202 (Figs. 1 and 4), said arm projecting from a hub 65

203 mounted to oscillate laterally by means of slots 203* in said hub, which slots receive trunnions 204 projecting from a fulcrum block 205 that is contained within the hub 203, said block 205 being pivotally supported upon a pin 206 projecting inwardly from the standard 31. This mounting of the hub 203 is simply to enable it to have universal movement, and, as any other universal mounting may be substituted therefor, I do not show the extreme specific details of said mounting. An arm 207 projecting rearwardly from the hub 203 is provided with a ball 208 freely movable therein. This ball 208 is provided with a shank 208* slidably mounted in one end of a lever 209 which is mounted on a universal pivot 210, said lever 209 (see Fig. 4) having a roll 211 which is acted upon by a cam 212 carried by the shaft 34. As the universal 85 mounting of the lever 209, like that described for the hub 203, may be of any preferred well-known type, it is not necessary to illustrate it in detail. The lever 209 is provided with slots 209* to receive the trunnions 210* of the pivot member 210, these slots 209* providing means whereby said lever 209 may be oscillated laterally. A cam 212 is peripherally formed to act upon the roll 211 so as to impart to the looper its 90 in-and-out movements, a suitably connected spring 213 (Fig. 4) causing the lever to follow such movements of the cam. Said cam is formed with a groove 214 (Figs. 6 and 7), which groove receives a roll 215 indicated 100 by dotted lines in Fig. 4, said roll being mounted on a pin carried by the lever 209. The cam groove 214 imparts to the lever the motions which transmit lateral motions to the looper. The combined cam action is 105 such of course that the looper has no movements in a straight line, said looper having in practice a motion which might be best described as following the path somewhat of the "numeral 6" so as to carry the thread 110 around the needle and then to move to a greater distance from the needle, and then return. It is obvious that during this operation the shank 208* of the ball 208 will reciprocate in the socket provided therefor 115 in the end of the lever 209.

The loop spreader comprises a hook-shaped member 216 (Fig. 6) formed at the end of the curved portion 217 (Figs. 1, 3 and 5) of a rockshaft 218 mounted in a bearing 219 supported by a suitable bracket 220. The rear end of the rockshaft 218 has an arm 221 connected by a link 222 with the outer end of an arm 223 (Figs. 3, 6 and 14) 120 which is pivotally supported on the sleeve 81 hereinbefore described. At the point where the link 222 and arm 223 are connected, a roll 224 is mounted, said roll entering the cam groove 111 in the disk 92. The object of the swinging arm 223 is to 125 130

keep the roll 224 in proper position to be acted upon by the cam groove 111. Said cam groove 11, as will now be understood, serves to actuate not only the loop spreader but also the presser foot lock hereinbefore described.

As indicated in Fig. 4, a suitable oscillating guide for the needle is indicated at 225. I do not show the details of the mounting 10 of said needle guide so that it can oscillate, as the same may be constructed as in my application 664,769, filed August 18, 1911.

To hold the loop of thread aside for the 15 needle to pass through the loop formed by the looper 201, I provide a simple and durable device consisting of a projection or hook 226 (Fig. 4) which is connected to the needle carrier in such position that the end of said hook or loop holder will be in advance of the 20 tip of the needle. In operation this hook moves to a low enough point so that the looper 201 will carry the thread around it just before the needle enters the loop.

In order that the presser foot may be 25 lifted whenever desired by the operator, I provide such a structure as illustrated in Fig. 5, the arm of the presser foot having a rearwardly extending lug or projection 227 in position to be engaged by one end of a lever 228 pivoted at 229 to any suitable part of the machine, the other or rear end of the lever 228 extending over the upper end of the rod 114 which, as hereinbefore explained, may be operated by a treadle not shown. 30 Normally the space between the upper end of the rod 114 and the rear end of the lever 228 is such that it is only during the last portion of the upward movement of the rod 114 that the lever 226 is actuated to raise the 35 presser foot.

Having described my invention, I claim:

1. In a sewing machine, the combination with the stitch forming mechanism thereof, of an oscillating awl, a slide for shifting the 45 awl in the direction of its axis of oscillation, a lever for actuating the slide, a sleeve adjustable longitudinally of said lever, a tubular block in which said sleeve is pivotally mounted, and means for adjusting said tubular block in the direction of the length of said lever.

2. In a sewing machine, the combination with the stitch forming mechanism thereof, of an oscillating awl, a slide for shifting the 55 awl in the direction of its axis of oscillation, a lever for actuating the slide, a sleeve adjustable longitudinally of said lever, a tubular block in which said sleeve is pivotally mounted, said tubular block having a rack, a pinion engaging said rack, and a handle for manually rotating said pinion.

3. In a sewing machine, the combination with the stitch forming mechanism thereof, of an oscillating awl, a slide for shifting the

awl in the direction of its axis of oscillation, 65 a lever for actuating the slide, a sleeve adjustable longitudinally of said lever, a tubular block in which said sleeve is pivotally mounted, said tubular block having a rack, a pinion engaging said rack, a handle for 70 manually rotating said pinion, and means for adjustably determining the limits of movement of the pinion and rack.

4. In a sewing machine, the combination with the stitch forming mechanism thereof, 75 of an oscillating awl, a slide for shifting the awl in the direction of its axis of oscillation, a lever for actuating the slide, a sleeve adjustable longitudinally of said lever, a tubular block in which said sleeve is pivotally 80 mounted, said tubular block having a rack, a pinion engaging said rack, a handle for manually rotating said pinion, and means for adjustably determining the limits of movement of the pinion and rack, said 85 means comprising a pair of fingers adjustably secured to one end of the pinion, and a stop pin mounted between said fingers.

5. In a sewing machine, the combination with the stitch-forming mechanism thereof, 90 of an oscillating awl, a slidable member for shifting the awl in the direction of its axis of oscillation, a lever for actuating said slid- 95 able member, a pivot member movable lengthwise of said lever, a slidable block adapted to receive the pivot thereof and provided with a rack, and a revoluble pinion meshing with said rack.

6. In a sewing machine, the combination with the stitch-forming mechanism thereof, 100 of an oscillating awl, a slidable member for shifting the awl in the direction of its axis of oscillation, a lever for actuating said 105 slid- able member, a pivot member movable lengthwise of said lever, a slidable block adapted to receive the pivot thereof and provided with a rack, a revoluble pinion meshing with said rack, and a manually operated handle for rotating said pinion.

7. In a sewing machine, the combination with the stitch-forming mechanism thereof, 110 of an oscillating awl, a slidable member for shifting the awl in the direction of its axis of oscillation, a lever for actuating said 115 slid- able member, a sleeve movable lengthwise of and surrounding said lever and provided with a projecting pivot, a slidable block adapted to receive said pivot, and means removed from said lever for adjusting said block in the direction of the length 120 of said lever.

8. In a sewing machine, the combination with the stitch forming mechanism thereof, of an oscillating awl, a slidable member for shifting the awl in the direction of its axis 125 of oscillation, a lever for actuating said slid- able member, a sleeve movable lengthwise of said lever and provided with a projecting

pivot, a slideable block adapted to receive said pivot, and having a rack thereon, and a revolute pinion meshing with said rack.

9. In a sewing machine, the combination
5 with the stitch forming mechanism thereof,
of an oscillating awl, a slideable member for
shifting the awl in the direction of its axis
of oscillation, a lever for actuating said
slideable member, an adjustable block, means
10 removed from said lever for adjusting the

position of said block, and a member freely
movable lengthwise of said lever and mov-
able endwise thereon pivotally connected to
said block.

In testimony whereof I have affixed my 15
signature, in presence of two witnesses.

EDWARD ERICKSON.
